UNITED STATES PATENT OFFICE.

JOSEPH FLAX, OF CHICAGO, ILLINOIS.

SPOOL.

1,207,010.

Specification of Letters Patent.

Patented Dec. 5, 1916.

Application filed February 8, 1916. Serial No. 76,997.

To all whom it may concern:

Be it known that I, JOSEPH FLAX, a citizen of the United States, residing at Chicago, in the county of Cook and State of Illinois, have invented certain new and useful Improvements in Spools; and I do hereby declare the following to be a full, clear, and exact description of the invention, such as will enable others skilled in the art to which it appertains to make and use the same, reference being had to the accompanying drawings and to the letters and figures of reference marked thereon, which form a part of this specification.

This invention relates to new and useful improvements in spools and relates more particularly to thread spools such as are commonly used by tailors.

To this end and to such others as the invention may pertain, the same consists in providing, in connection with one end of a spool, an open trough or chamber within which is placed beeswax, the bottom of the chamber being such as to render it convenient at all times for the tailor to wax the thread.

The invention is illustrated in the accompanying drawings which, with the numerals of reference marked thereon, form a part of this specification and in which:

Figure 1 is a perspective view of a spool constructed in accordance with my invention, and Fig. 2 is a central section of the same.

Reference now being had to the details

of the drawings by numeral, 1 represents a spool of ordinary form and construction, one end of which is recessed or cut away as shown at 2 to form a spherical concaved chamber for the reception of wax 3, the width of the chamber being such as to permit the pressing of the thread by the thumb of the operator into contact with the wax contained within the chamber, the surface of the wax being flush with the plane of the outer edge of the chamber so as to in no way interfere with the packing of the spool for shipment or storage.

It will be noted at once that, in view of the annoyance occasioned by a tailor by reason of the misplacing or loss of the wax required for use in his work, the advantage of providing a thread spool with a chamber of this kind is at once evident.

Having thus described my invention, what I claim to be new and desire to secure by Letters Patent is:

As an improved article of manufacture, a spool having at one end, surrounding the opening therein, an annular wax-receiving chamber, the bottom wall of which is inclined from its outer edge inward toward the center.

In testimony whereof I hereunto affix my signature in presence of two witnesses.

JOSEPH FLAX.
